REFRIGERATED LIQUID DISPENSER

Orden E. Ihle, Glendale, Calif., and Thomas Norman, Chicago, Ill., assignors to Orden E. Ihle, doing business as Ihle Manufacturing Company, Glendale, Calif.

Application December 24, 1951, Serial No. 263,104

5 Claims. (Cl. 62—141)

1

The present invention relates to liquid dispensers and, more particularly, to a refrigerated liquid dispenser having a receptacle for a supply of the liquid to be dispensed and having means for dispensing liquid from the receptacle. The invention has particular utility as a dispenser of such beverages as soft drinks, juices and the like, and will be considered in connection therewith as a matter of convenience.

In general, the present invention contemplates a dispenser which includes a supporting structure providing a retainer for the receptacle, the retainer preferably having the form of a base or seat on which the receptacle may be placed. The invention also includes a refrigerating means which is adapted to be disposed within the receptacle so as to contact directly the liquid to be refrigerated. Also, the invention includes agitating means for agitating the liquid in the receptacle, agitation being particularly necessary when the dispenser is used in connection with fruit juices since these frequently contain solid material which tends to settle out otherwise.

An important object of the invention is to provide a dispenser wherein the refrigerating means is pivotally connected to the supporting structure adjacent its upper end so that it can be swung outwardly into a position permitting removal of the receptacle from the retainer. With this construction, the receptacle may be removed readily for cleaning, which is an important feature, a related object being to provide a receptacle having a smooth interior so that it may be cleaned readily.

Another object is to provide a refrigerating means which includes a refrigerating element adapted to be disposed adjacent the bottom of the receptacle, and which includes supporting means for the refrigerating element which is connected at its lower end to the refrigerating element and which is pivotally connected at its upper end to the supporting structure.

Another object is to provide a refrigerating means which includes refrigerant tubes running through the supporting means, such refrigerant tubes having flexible portions adjacent the pivotal connection of the supporting means to the supporting structure so as to permit pivotal movement of the supporting means.

Another important object of the invention is to provide a dispenser wherein the agitating means includes an agitator located below and centrally of the refrigerating element, which is preferably tubular and which is centrally located in the receptacle. With this construction,

2

the agitator produces circulation of the liquid around the refrigerating element to prevent formation of frost or ice thereon, which is an important feature of the invention.

5 Another object is to provide driving means below the receptacle and operatively connected to the agitator for rotating the agitator.

Still another important object is to provide a driving means which includes a rotatable driving element magnetically coupled to the agitator, thereby avoiding any necessity for a shaft through the bottom of the receptacle, or extending downwardly thereinto from the top. With such magnetic coupling between the driving element and the agitator, removal of the receptacle from the supporting structure for cleaning, or for other purposes, is greatly facilitated, which is an important feature.

Another object is to provide means for latching the refrigerating means in its inoperative position so that the receptacle may be disengaged therefrom readily.

The foregoing objects and advantages of the present invention, together with various other objects and advantages thereof which will become apparent, may be attained with the exemplary embodiment of the invention which is illustrated in the accompanying drawing and which is discussed in detail hereinafter. Referring to the drawing:

10 Fig. 1 is a view, partly in side elevation and partly in vertical section, of a refrigerated liquid dispenser which embodies the invention;

15 Fig. 2 is a top plan view of the refrigerated liquid dispenser;

20 Fig. 3 is a sectional view taken along the arrowed line 3—3 of Fig. 1; and

25 Fig. 4 is an enlarged, fragmentary sectional view taken along the arrowed line 4—4 of Fig. 2.

30 Referring to the drawing, the numeral 10 designates a housing which serves as a supporting structure for various elements of the dispenser, the supporting structure or housing providing a space for a receptacle 11 adapted to contain a supply of a liquid to be dispensed. The receptacle 11 is substantially hemicylindrical in the particular construction illustrated and preferably is formed of a transparent material so that the liquid therein can be viewed from the outside. The housing 10 also provides a retainer for the receptacle, the retainer preferably being a simple base or seat 12 on which the receptacle is adapted to rest. Disposed below the seat 12 and communicating with the interior of the receptacle 11 is a dispensing valve 13 through

which liquid may be dispensed from the receptacle in the usual manner. A removable cover 14 is also provided.

Adapted to be disposed within the receptacle 11 is a refrigerating means 17 which includes a refrigerating element 18 adapted to be disposed centrally of the receptacle adjacent the bottom thereof. The refrigerating element is tubular and includes a housing or jacket 19 in which is disposed a helical refrigerant coil 20. The refrigerating element 18 is suspended within the receptacle 11 by a supporting means 21 which is illustrated as having the form of a generally vertical tubular support 22 connected at its lower end to the refrigerating element. The supporting means 21 also includes a bifurcated element 24 the arms of which are pivotally connected to supporting brackets 25 on the housing 10 by pins 26. The brackets 25 also carry pins 27 which extend through arcuate slots 28 in the arms of the bifurcated element 24, the pins 27 serving to limit pivotal movement of the supporting means 21. Each slot 28 is provided at one end with an offset portion, best shown in Fig. 4, which serves to receive the corresponding pin 27 to latch the supporting means 21 in an inoperative position. The pins 27 are biased into the offset portions of the slots 28 by springs 29.

As clearly shown in Fig. 1 of the drawing, the refrigerating means 17, i. e., the refrigerating element 18 and the supporting means 21 therefor, are pivotable about the axis of the pivot pins 26 from an operative position, shown in solid lines, to an inoperative position, shown in broken lines. When the refrigerating means 17 is pivoted to its inoperative position, the receptacle 11 moves outwardly into a position wherein it clears the base or seat 12 so that it may be moved downwardly to disengage it from the refrigerating means, the refrigerating means being latched in the inoperative position by the pins 27. Thus, by pivotally connecting the refrigerating means 17 to the supporting structure or housing 10 in this manner, the receptacle 11 may be removed for cleaning, or for other purposes, very readily, which is an important feature of the invention.

As best shown in Fig. 2 of the drawing, a liquid-phase refrigerant tube 30 and a vapor-phase refrigerant tube 31 extend downwardly into the tubular support 22, these tubes being connected at their lower ends to the refrigerant coil 20. These tubes extend upwardly into a hollow portion 32 and outwardly through an opening 33 into the space between the arms of the bifurcated element 24. In this zone, the tubes 30 and 31 are provided with flexible portions 34 and 35, respectively, these flexible portions permitting pivotal movement of the refrigerating means 17 in the manner hereinbefore described. Disposed alongside the tubes 30 and 31 is another tube 36 which may form part of a thermostat means for controlling the temperature of the liquid in the receptacle 11, this tube 36 also having a flexible portion 37 between the arms of the bifurcated element 24. The tubes 30, 31 and 36 are connected to a suitable refrigeration system, not shown, disposed within the housing 10.

Carried by the bottom wall of the receptacle 11 and centrally located with respect to the tubular refrigerating element 18 is a rotatable agitator 41 which carries at least one bar magnet and which is shown as having two bar magnets 42 embedded therein. Disposed below the receptacle 11 and carried by the housing 10 is a driving means for rotating the agitator, the driving means includ-

ing a driving element 44 which is disposed just below the bottom wall of the housing 10 in registry with the agitator 41. The driving element 44 has one or more bar magnets 45 embedded therein and may be driven in any suitable manner, as by an electric motor 46.

Thus, the agitator 41 is magnetically coupled to the driving element 44 so that the agitator is driven without any direct mechanical connection through the bottom wall of the receptacle 11. This is an important feature since it greatly facilitates removal of the receptacle 11 for cleaning, and also greatly facilitates cleaning of the receptacle.

It will be noted that the agitator 41 is centrally located with respect to the tubular refrigerating element 18 and adjacent thereto. Consequently, circulation established by the agitator carries completely around the tubular refrigerating element, such circulation being, in general, upwardly through the interior of the refrigerating element and then downwardly around the exterior thereof. This circulation, in addition to maintaining any solids in the liquid in suspension, also prevents frost or ice formation on the refrigerating element 18, which is an important feature of the invention.

Although I have disclosed an exemplary embodiment of my invention herein for purposes of illustration, it will be understood that various changes, modifications and substitutions may be incorporated in this embodiment without departing from the spirit of the invention.

We claim as our invention:

1. In a refrigerated liquid dispenser, the combination of: a supporting structure providing a base for a receptacle; a receptacle adapted to seat on said base; refrigerating means adapted to be disposed in said receptacle and pivotally connected to said supporting structure; a rotatable agitator in said receptacle adjacent said refrigerating means; driving means for said agitator carried by said supporting structure, including a rotatable driving element below said receptacle and aligned with said agitator when said receptacle is on said base; and magnetic coupling means carried by said agitator and said driving element for operatively connecting said agitator to said driving element.

2. In a refrigerated liquid dispenser including a liquid containing receptacle adapted to move between an operative and an inoperative position, the combination of: an upright housing having a recess in one side thereof providing a base for the receptacle when the latter is in the operative position; refrigerating means disposed in said receptacle, said refrigerating means including a refrigerating element and including supporting means for said refrigerating element which is connected at its lower end to said refrigerating element and which is pivotally connected at its upper end to said housing, said supporting means being adapted to pivot laterally with said refrigerating element to permit said receptacle to move off said base to the inoperative position; a rotatable agitator in said receptacle adjacent said refrigerating element; and rotatable driving means outside said receptacle and operatively connected to said agitator for rotating same, the movement of the receptacle from operative to inoperative position disconnecting said agitator and said driving means.

3. A dispenser according to claim 2 wherein said rotatable driving means is positioned below said base.

4. A dispenser according to claim 3 wherein said rotatable driving means and said agitator are operatively connected by magnetic coupling means when said receptacle is in operative position and automatically disconnected by the movement of the receptacle from operative to inoperative position.

5. In a refrigerated liquid dispenser having a liquid-containing receptacle adapted to move between a first position in which said receptacle is retained in a housing and a second position in which said receptacle is free of said housing, the combination of: a base in said housing on which said receptacle is adapted to seat when in said first position; a dispensing valve carried by said housing and communicating with the interior of the receptacle when the latter is in said first position; a rotatable agitator in said receptacle; rotatable driving means disposed below said base; magnetic coupling means carried by said agitator and said driving means operatively

connecting same only when said receptacle is in said first position; and a refrigerating element pivoted to said housing and extending within said receptacle, said refrigerating element being adapted to pivot laterally to permit movement of said receptacle between said first and said second position.
